(57) **CLAIM**

The ornamental design for a wireless presenter, as shown and described.

DESCRIPTION

FIG. 1 is a perspective view of a first embodiment of a wireless presenter, showing my new design;

FIG. 2 is another perspective view thereof;

FIG. 3 is a perspective view of the design in a detached configuration;

FIG. 4 is another perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a perspective view of a second embodiment of a wireless presenter;

FIG. 12 is another perspective view thereof;

FIG. 13 is a perspective view of the design in a detached configuration;

FIG. 14 is another perspective view thereof;

FIG. 15 is a front view thereof;

FIG. 16 is a rear view thereof;

FIG. 17 is a left side view thereof;

FIG. 18 is a right side view thereof;

FIG. 19 is a top plan view thereof; and,

FIG. 20 is a bottom plan view thereof.

The broken line showing of the wireless presenter is for the purpose of illustrating article and forms no part of the claimed design.

1 Claim, 20 Drawing Sheets
